CONCRETE SLAB

Maurice Deutsch, New York, N. Y.

Application February 26, 1937, Serial No. 127,888

16 Claims. (Cl. 72—68)

This invention relates to cellular reinforced concrete slabs and particularly to that type which are cast horizontally and subsequently used as wall, floor, partition or roof elements in the erection of so-called prefabricated buildings.

The principal objects of the invention are to provide a slab of this type having improved, permanently positioned hollow core members which form the cellular openings and which operate with other elements of the slab to increase its strength, to reduce its weight, and to lessen the cost of its fabrication; to completely insulate from each other, both thermally and acoustically, the two sections of such a slab at opposite sides of a median plane thereof, and to provide throughout for the expansion and contraction of such sections toward and away from each other and in a shearing fashion; to provide a waterproof seal between the two sections of the slab at all points where moisture or dampness might otherwise penetrate to the inner section of the slab; and to provide improved fastening means for securing the completed slabs together when erecting a building.

Other objects will appear from the following description.

Several forms of the improved building slab, and also the method of making it, are illustrated in the accompanying drawings, in which

Fig. 1 is a horizontal section through a wall slab and a portion of an adjoining one, the section being taken on the line 1—1 of Fig. 15, in such a plane as to include, and show the construction of, the fastening means for securing the slabs together;

Fig. 2 is a similar horizontal section through the adjoining portions of the slabs shown in Fig. 1, the section being taken on the line 2—2 of Fig. 15 in a plane where the fastening means does not occur;

Fig. 3 is a vertical section taken on the line 3—3 of Fig. 1;

Fig. 4 is a section taken on the line 4—4 of Fig. 3, the core members which form the cellular openings being omitted to show the manner in which the metallic fastening elements are associated with the reinforcing struts;

Fig. 5 is a vertical section through one of the slabs as it appears on the casting table, and illustrates the method of casting it;

Fig. 6 is a partial horizontal section through a completed slab and shows a modification of the strut illustrated immediately above it in Fig. 1;

Fig. 7 is a horizontal section taken on the line 7—7 of Fig. 15, and illustrates the manner in

which the wall slabs may be fastened together at the corner of a building;

Fig. 8 is a vertical section taken approximately on the line 8—8 of Fig. 5, and illustrates the fastening means at the upper and lower ends of 5 the slab shown in Figs. 1 and 5;

Fig. 9 is a similar section taken on the line 9—9 of Fig. 5;

Fig. 10 is a vertical section taken on the line 10—10 of Fig. 13, and also on the line 10—10 of 10 Fig. 12, through a portion of a slab on the casting table, the slab in this case being particularly adapted for use as a floor slab;

Fig. 11 is a vertical section of the same slab taken on the line 11—11 of Fig. 13, and on the 15 line 11—11 of Fig. 12;

Fig. 12 is a section taken on the line 12—12 of Fig. 10 and on the line 12—12 of Fig. 13;

Fig. 13 is a plan view of one corner of a floor slab as it appears on the casting table, the purpose of this view being mainly to show where the sections of some of the other figures are taken;

Fig. 14 is a detail perspective view of a portion of one of the metallic reinforcing struts illustrating the manner in which the fastening means shown in Figs. 10, 11 and 12 is associated with it;

Fig. 15 is a schematic representation in perspective of a portion of a building constructed from slabs made in accordance with the invention;

Fig. 16 is a vertical section taken on the line 16—16 of Fig. 15 through a portion of a building constructed of slabs made in accordance with the invention and illustrates the manner in 35 which the floor slabs may be fastened to the wall slabs;

Fig. 17 is a section taken on the line 17—17 of Fig. 16, and on the line 17—17 of Fig. 15;

Fig. 18 is a horizontal section taken on the 40 line 18—18 of Fig. 17, and

Fig. 19 is a vertical section illustrating a modified way in which the floor slabs may be fastened to the wall slabs.

The wall slab shown in Fig. 1, comprises in 45 general a body of concrete cast around a series of hollow core members or forms left permanently in the slab. Between adjacent core members, and at the ends of the slab, the concrete forms struts, but the transverse continuity of 50 these struts is interrupted by interposed waterproof insulating and expansion material so that the slab is divided along a median plane into an inner section and an outer section. The two sections of the slab are tied together by metallic 55

- transverse reinforcing struts embedded in the concrete struts. The two sections of the slab are reinforced by metallic members extending through them and which span the reinforcing struts and lie outwardly of the core members. Metallic fastening elements rigidly secured to certain of the strut reinforcements are cast within the slab at suitable points to enable the slabs to be bolted together.
- 10 The concrete forming the inner section is shown at 1 and that forming the outer section is shown at 2. At the ends of the slab and at spaced intervals there is a concrete strut 3. Metallic reinforcing struts 4 are embedded in the concrete struts. All elements that make up one of these reinforcing struts are rigidly secured together or otherwise made unitary, as will later appear. Metallic bars, or so-called "flats" 5, spaced every few feet apart are welded or otherwise rigidly secured to the upper edges of the reinforcing struts 4 and extend through the concrete of the upper section in a direction parallel with the upper face of the slab. Similar bars secured to the lower edges of the reinforcing struts 4 likewise extend through the concrete of the lower section. The upper bars 5 support and have welded or otherwise secured to them a layer of wire mesh 6, and likewise a layer of wire mesh is secured to the lower bars 5. The bars 5 and the wire mesh 6 reinforce the concrete forming the inner and outer walls of the slab. It will now be noted that all of the metallic reinforcing elements are rigidly connected together to make the entire reinforcing structure continuous and unitary.
- A hollow core member is located between each pair of reinforcing struts 4. Each core member comprises two independent opposing strips of waterproofed fibrous material 7 and 8, which extend longitudinally between the reinforcing struts. The two sheets are transversely arched outwardly and the edge portions lie in close proximity as indicated at 9. Each strip is of such a width that it extends substantially the entire distance from one reinforcing strut to the next one. Each pair of opposing sheets form a tunnel like passage or opening extending vertically through the slab. The number of core members forming the openings in the slab may be varied to suit requirements. There may be one or more. The span of each core member may approximate 4' so ordinarily there will be several core members in one slab.
- The opening at the upper and lower ends of the hollow core members is closed by two flat sheets of waterproofed fibrous material 7^a and 8^a (Fig. 8), the sheet 7^a cooperating with the lower core sheet 7 to close the lower part of the passage and the sheet 8^a cooperating with the upper core sheet 8 to close the upper half of the passage. Interposed between the adjacent edge portions 9 (Figs. 1 and 2) of the fibrous core sheets is a layer of plastic non-hardening waterproof material 10, such as thick mastic or a mixture of similar plastic material and fibers. At the extreme ends of the slab the edge portions 9 of the fibrous sheets are extended or supplemented beyond the last reinforcing strut 4 as shown at 9' in Fig. 2, and the non-hardening material 10 is likewise extended between them so that both the fibrous material and the non-hardening material will extend to the extreme end of the slab. Likewise, at the upper and lower ends of the slab (Fig. 9) a layer of non-hardening material 10 lying between waterproofed fibrous sheets 9'

is sandwiched between the end sheets 7^a and 8^a and extends to the extreme end of the slab. Thus the concrete forming the inner section 1 of the slab is not integral with the concrete forming the outer section 2. The sections are separated at 5 every concrete strut, and completely around the peripheral portion of the slab, by the non-hardening material lying between sheets of fibrous material. The expansion joint formed by the non-hardening material 10 permits the two sections of 10 the slab to expand and contract toward and away from each other and with a sliding or shearing action one upon the other, and the fibrous material cooperates with the non-hardening material 10 to insulate the two sections of 15 the slab from each other both thermally and acoustically. Moreover, the non-hardening material 10 cooperating with the waterproofed fibrous sheets between which it lies acts as a seal and prevents moisture or dampness from 20 reaching the inner section of the slab at all points. The reinforcements 4 embedded in the concrete struts, of course, tie the two sections of the slab together.

The inner face of the slab has a layer 11 of 25 any suitable material that may serve as the interior finish of the building, such as Keene cement, acoustic plaster, or the like, and the outer surface of the slab has a layer 12 of any suitable material that is adapted for the exterior 30 finish of the slab. This layer may be finished to resemble brickwork, stone, wood siding, or to give any effect desired.

Before proceeding with a description of the fastening means for securing the slabs together 35 when erecting a building, it should be noted that each reinforcing strut 4 comprises an I-shaped member whose web has been expanded, as best shown in Fig. 14. (This figure, however, shows the fastening means for the floor slabs to be 40 hereinafter described, and not the fastening means for the wall slabs now to be described.) This results in two T-shaped bars with diagonals connecting the central flange 4' of one T-bar with the central flange 4' of the other T-bar. 45

The end strut reinforcements have secured to them, as by welding, a pair of angle irons 13 which extend transversely of the slab and bear against the inner face of the central flanges 4' of the T-shaped bars (Figures 1, 3 and 4). A metal strap 50 14 is welded or otherwise secured to the angle irons 13. The web of this strap is provided with an opening 15 (Figure 4) which is slightly elongated vertically. A tube 16, preferably of fibrous material, having the same cross sectional shape 55 as the opening 15, extends from the perforated web of the strap 14 through the concrete to the end of the slab. The face of the strap 14 and its opening 15 are accessible from the interior of one of the core openings. 60

When it is desired to bolt two of the slabs together in erecting a wall, the edge surfaces of the slabs are placed in abutting relation as shown at the right in Figure 1, and a bolt 17 is inserted through the tubes 16. When nuts 18 65 are at the extremities of the bolt are tightened, the slabs are retracted tightly against each other. Of course the bolt 17 may have a head at one end in place of the second nut shown in the drawings. As best shown at the left in Figure 1, the 70 meeting edge surfaces of the slabs are preferably shaped to provide a recess 19 extending vertically down the edge of the slab. This recess has a deeper central recess 20. At each side of the recess 19 is a small recess 21 which extends par- 75

allel with the recess 19. When two slabs are positioned prior to bolting, a key member 22, shown at the right in Figure 1, is inserted between the central recesses 20. This key member may be cast from concrete or any other suitable material and has an opening to accommodate the bolt 17. A packing 23 of waterproof non-hardening material, such as mastic, or a mixture of a similar plastic material and fibers, is inserted 5 in the shallower recess 19 at each side of the key 22. This packing also serves as a yielding joint to permit expansion and contraction of the slabs relative to each other. Caulking cords 24 are placed in the recesses 21. It will thus be seen that when the slabs are bolted together, a tight waterproof expansion joint is effected. If desired the key 22 may be cast integral with one of the slabs.

In order to permit insertion of the bolt 17 and 20 tightening of the nuts on the bolt, the inner section of the slab is provided with a hand hole 25 near each of the fastening assemblies. The hand hole communicates with the particular core opening through which the corresponding fastening 25 assembly is accessible. The fastening assembly lies wholly within the slab and access to the interior of the slab, made possible by the hand holes 25, enables the slabs to be bolted together.

It should be particularly noted that the reaction of the clamping bolt is not directly against the concrete. The fastening bolts retract the straps 14 against the angle irons 13 and these in turn are retracted against the webs 4' of the strut reinforcement 4. Thus the clamping strains 35 are all taken up by the metallic reinforcing structure.

Fastening assemblies such as those shown in Fig. 1 preferably occur near the upper corners of the wall slabs and near their lower corners as 40 diagrammatically indicated at 26 and 27 in Fig. 15. Fig. 2 is a section through the joint shown at the right in Fig. 1 taken in a plane where no fastening assembly occurs, for instance, on the line 2-2 of Fig. 15.

Wherever a fastening assembly occurs, the expansion and waterproof material 10 abuts against the fibre tubes 16 as shown in Fig. 3, and the fibrous core sheets are slotted to receive the flanges of the straps 14. The elongated opening 15 in the strap 14 and the elliptical shaped tube through which the bolt 17 passes, provides enough play or tolerance to permit a slight vertical movement of one slab relative to the adjacent one.

Wherever greater strength is required at the concrete struts, two metallic reinforcing struts 4 may be employed therein as shown in Fig. 6. In other words, the strut shown in Fig. 6 may, if desired, be substituted for the strut shown immediately above it in Fig. 1. In this case the edge portions of the fibrous core sheets are extended or supplemented between the metallic struts as indicated at 9' and the non-hardening material 10 is extended between them.

The method of casting one of the improved slabs is illustrated in Fig. 5. A casting table of any suitable type may be employed having a horizontal surface A and side walls B forming a mold of the desired shape and size. Forms C of 70 the proper configuration are utilized to impart the desired shape to the surfaces of the slab that are to mate with corresponding surfaces on other slabs. The first step is to deposit a layer of Keene cement or other material 11 that is to 75 constitute the interior finish of the slab. A layer

of concrete is then deposited up to the level indicated at D. The entire metallic reinforcing structure, including the fastening assemblies, is now positioned in the mold. If desired the upper bars 5 and the upper layer of wire mesh 6 may be omitted at this stage and welded in place later as will hereinafter appear. More concrete is now deposited to bring the level to the plane indicated at E. The sequence of the steps so far described may be varied if desired. For instance, the reinforcing structure may be positioned at an earlier stage and the concrete forced through under and around the part that is to be embedded. The sheets 7 constituting the lower halves of the core members, and the end closure sheets 7a (Fig. 8,) are now positioned and held in place in any suitable manner while more concrete is forced in to completely fill the space around the lower half of the cores up to the level indicated at F. Wherever necessary the edge portions of the fibrous core sheets may have slots or openings 28 to allow the concrete to be introduced through them. The lower fibrous core sheets are supplemented wherever necessary as indicated at 9' in Figs. 2 and 6 and at 9" in Fig. 9 and then the layer of non-hardening material 10 is applied at all places where it is to occur.

It will be understood that appropriate forms are employed to form the hand holes 25 in the lower section of the slab and to provide any other desired openings to receive heat registers, ventilators and the like, and that all necessary door and window frames may be set in place before pouring the concrete. Also during the casting of the lower section of the slab, accessory elements such as pipes, conduits, lighting fixtures, or similar devices represented at 29, and which are to extend transversely through the lower section of the slab, are positioned, and if the slab is to be provided with bolts or similar 40 accessory elements represented at 30, for attachment to interior devices when the building is erected, tubes 31 may be cast in place to receive them.

It is important to note that at this stage during casting of the slab only the lower halves of the core members have been positioned and that the interior of the core members is still accessible. This makes it possible to perform at this time those operations in the interior portion of the slab that could not be performed if the slab were completed. For instance, the transverse pipe or conduit 29 may at this time be suitably connected with a pipe or conduit 32 that is to pass vertically through the wall slab, and the bolts 30 50 may at this time be inserted in the tubes 31 until they rest on the surface of the casting table. When the slab is subsequently removed from the casting table, the bolts 30 may be drawn through the tubes and thus made to project into the interior of the building for attachment to the appropriate devices. Moreover, by completing the lower section of the slab before the upper halves of the core members are positioned and before the concrete forming the upper slab section is 55 poured, it can be definitely ascertained that the concrete has reached all points under and around the lower halves of the core members, thus insuring that no voids or open spaces will 60 be left in the concrete.

The fibrous sheets 8 constituting the upper halves of the core members and the end closure sheets 8a are now positioned and supplemented wherever necessary as at 9' in Figs. 2 and 6 and at 9" in Fig. 9. Concrete is then poured over 75

and around the upper halves of the cores to the level indicated at G. If the span of the core members happens to be quite long, or if the fibrous material does not have sufficient strength 5 of itself to support the weight of the concrete above it, the upper halves of the core members may be reinforced in any suitable way to prevent them from collapsing when concrete is poured over them as by the use of props, supports or 10 braces positioned inside the core members or positioned over the upper halves of them. The upper bars 5 and the wire mesh 6 are now welded to the upper edges of the reinforcing struts 4 if they were not in place when the rest of the 15 reinforcing structure was positioned. More concrete is then deposited to bring the level to the plane indicated at H, and finally the material 12 for the exterior finish of the slab is deposited and finished off in the desired way. It will be understood that the casting table may be vibrated 20 at any stage of the process. Also to facilitate hardening and curing of the mass heat or vacuum may be applied at any stage. After the slab has been allowed to set, it is removed from the 25 casting table and is ready for use in the erection of a building.

Fig. 7 shows how a wall slab constructed exactly like the one already described and shown at the right in this figure can be fastened to an 30 other wall slab at the corner of a building. The edge surface of the slab shown at the right may be positioned against an edge interior face portion of another slab shown at the left. The left-hand slab is provided with a special fastening 35 assembly to cooperate with the fastening assembly in the righthand slab and which has already been described. In the lefthand slab additional reinforcing struts 4^a and 4^b may be employed and angle irons 13' similar to those 40 shown at 13 in the other figures may span the flanges of the reinforcing struts 4 so that they will lie substantially parallel with the corresponding angle irons 13 in the adjacent slab. A strap 14' reacts against the angle irons 13' in the manner previously described, and the bolt 17 reacts 45 against the strap 14' and the strap 14 in the other slab when the joint is made. The end portion of the lefthand slab in Fig. 7 may have a small hollow core member 7'-8' corresponding 50 in general with the core members previously described, and the waterproofing and expansion material 10 is interposed, as shown, between the inner and outer sections of the slab and extends to the end thereof. If desired, the extreme end 55 of the slab may have applied to it a coating of waterproof cement finish or the like 33 which conceals the expansion material 10 and provides an exterior finish at the end of the slab.

The upper and lower ends of the wall slab 60 shown in Figs. 1 and 5 may be provided with fastening assemblies to enable the upper and lower edge surfaces of the slab to be bolted to floor slabs. As these additional fastening assemblies do not show in the sections of Figs. 1 and 65 5, they have been illustrated in Figs. 8 and 9. These figures are sections taken in a plane substantially at right angles to the plane of Figs. 1 and 5, the section of Fig. 8 being taken on the line 8-8 of Fig. 5 and the section of Fig. 9 being taken on the line 9-9 of Fig. 5. It will be understood that these figures show the fastening assembly at only one end of the slab because the fastening assembly at the other end may be identical in construction as will later appear from 70 the description of Fig. 16. In this case a metal

plate 34 spans the central flanges 4' of the reinforcing strut and is welded or otherwise secured to them. One flange 35 of an angle plate is welded or otherwise secured to the plate 34 so that its other flange 36 lies parallel with the edge 10 surface of the slab to be bolted to the floor slab. Flange 36 is perforated to receive the end of a fibre tube 37 which is suitably held in place during casting of the slab. This tube receives the bolt that clamps the slabs together.

The floor slabs may be substantially the same in construction as the wall slabs already described the principal difference being in the construction and location of the fastening assemblies. Figs. 10, 11, 12 and 14 illustrate one form 15 of fastening means for the floor slabs. In the case of the floor slabs the clamping bolts, one of which is preferably located near each corner of the slab, extends at right angles to the upper and lower faces of the slab, and thus the fiber tubes 20 which receive the bolts should also extend in this direction. This is accomplished by welding or otherwise attaching a U-shaped channel 38 to a plate 39 which spans the central flanges 4' of the reinforcing strut and is welded or otherwise secured to them. The fiber tubes 40 which receive the clamping bolts fit in perforations in the flanges of the channel member 38 and are suitably held in place during casting of the slab. During casting of the floor slabs, forms 41 and 42 30 may be employed to give the proper shape to the faces of the floor slab where they meet the edge surface of the wall slabs to receive the key 22, the packing or expansion material 23 and the caulking cords 24.

For a better understanding of the assembled slabs shown in Figs. 16 and 17, it will be helpful at this stage to point out again just where the fastening assemblies on the various slabs occur. By reference to Fig. 15 it will be seen that the fastening assemblies for the vertical meeting edges of the wall slabs occur approximately at the points indicated at 26 and 27, while the fastening assemblies for the horizontal meeting surfaces between the wall slabs and the floor 45 slabs, or between the roof and floor slabs, occur approximately at the places indicated at 43, 44, 45 and 46. Fig. 16 is a vertical section taken approximately on the line 16-16 of Fig. 15, through the fastening assemblies for the floor 50 and wall slabs, looking toward the joint between the wall slabs which joint lies just to the rear of the plane of the section. Fig. 17 is a section taken on the line 17-17 of Fig. 15, and also on the line 17-17 of Fig. 16. Now referring to 55 Figs. 16 and 17 it will be seen that in assembling the wall and floor slabs, and also the roof slabs (which may be constructed substantially like the slabs hereinbefore described), bolts 17 are inserted through the fiber tubes 40 of the floor 60 slabs and the corresponding fiber tubes 37 of the wall slabs. By tightening the nuts on these bolts, the slabs are firmly secured together. Insertion of the bolts and tightening of the nuts is made possible by the hand holes 25 which permit access to the interior of the slabs.

Instead of inserting the ends of the floor slabs between the wall slabs as shown in Fig. 16 they may be supported in the manner shown in Fig. 19. The upper edge surface of one wall slab may 70 be fastened directly to the lower edge surface of the superposed wall slab by fastening means on both of these slabs similar to that shown in Figs. 8 and 9. Near the upper edge of the lower wall slab a metal plate 47 may be welded to the 75

reinforcing struts so that the outer surface of the plate will be substantially flush with the interior surface of the slab. Angle irons 48 welded to the plate 47 provide horizontal ledges 49 which support the end of the floor slab. Another plate 47' and angle irons 48' may likewise be secured to the reinforcing struts near the lower edge of the superposed wall slab so that the floor slab lies between the horizontal flanges 49' of the upper angle irons and the horizontal flanges 49 of the lower angle irons. The fastening assembly at the end of the floor slab may be substantially like that shown in Fig. 16. When the floor slab is positioned, the bolts are inserted through the fiber tubes 40 of the floor slab and through the perforations in the horizontal flanges 49 and 49' of the angle irons 48 and 48'. Any portions of the fastening means which would ordinarily be exposed in the interior of the building may be concealed by copings or fillets or other architectural expedients indicated at 50. If the passages formed in the slabs are to be utilized as ducts for ventilating purposes, or for conveying hot air, or to receive pipes or conduits, the concrete of the wall slabs, where they join may be provided with openings or passages 51, and if the passages in the wall slabs are to communicate with the passages in the floor slabs, the concrete at the end of the floor slabs, and at the adjoining faces of the wall slabs, may be provided with openings 52. Similar openings may be provided in the slabs shown in Fig. 16 to establish communication between the passages in the wall slabs and those in the floor slabs.

It will now be noted that in every case the slabs are bolted together by clamping metal to metal. In other words, the clamping forces of the bolts are transmitted directly to metallic elements which in turn transmit them to the unitary metallic reinforcing structure. This also causes the metallic structure throughout the building to be substantially continuous. The fastening instrumentalities may be entirely concealed within the slabs thus leaving no projecting members on the exterior or interior surfaces of the building where the slabs join. The hand holes 25 may be closed by plates or in any other suitable way after they have served their purpose of permitting the slabs to be bolted together. My improved system of bolting the slabs together permits dismantling, salvaging, reassembling, enlarging or altering the structures economically.

55 The waterproofed fibrous material provides thermal, acoustic or other vibration insulation between the inner and outer sections of the slabs, and is continuous, in effect, throughout the length and width of the slabs. The non-hardening, waterproof material used for the expansion joints also provides thermal, acoustic, or other vibration insulation and also serves as a seal against moisture and dampness at all points where it might otherwise penetrate to the inner section of the slab. The inner and outer sections of each slab may expand and contract toward and away from each other and in a sliding or shearing fashion and yet the two sections of the slab are structurally united and tied together by the reinforcing struts. The improved slab might be thought of as a structural sandwich in which each of the two slices or sections is completely lined at its inner channeled or recessed face with waterproofed fibrous material 75 (the sheets which form the hollow core mem-

bers and any sheets which complete their continuity) and sandwiched between these lined sections, at all places where they come together, is the filling of plastic non-hardening waterproof material. In some cases the plastic non-hardening material may be omitted so that at all places where the two sections of the slab come together the fibrous lining of one section will abut directly against the fibrous lining of the other section.

10 The waterproofed sheets of fibrous material used for the core members may be preformed to the desired shape, or semi-formed, or shaped to the desired configuration during casting of the slab. Their flexibility makes it possible to use them for almost any practical requirements as to form as they can be properly adjusted and shaped during casting of the slab. Their arched construction increases the strength of the slab and materially lessens its weight and cost of 20 production. The amount of concrete employed is reduced to a minimum.

15 The term "concrete" as used throughout the specification and claims is intended to include any equivalent self-hardening, plastic material, such as gypsum and similar materials ordinarily used in the construction of buildings.

25 While I have described the fabrication of my improved slab by the horizontal table method, which produces a slab suitable for use in the erection of so-called "prefabricated" buildings, it will be understood that the invention is not limited to a slab made by that method. The invention includes slabs of such construction that they may, if desired, be fabricated in situ as the construction of the building progresses in accordance with the usual building methods or other appropriate ones.

30 I claim:

35 1. A composite building slab comprising a body 40 of concrete divided into two sections along a median plane lying parallel with its major faces, the interior face of each of said sections having depressions which cooperate with the corresponding depressions in the other slab section to form 45 interior openings in the composite slab, sheet material lining substantially the entire inner face of each slab section, non-hardening waterproof plastic material interposed between the sheet material at all points where portions of the two 50 slab sections come together, and reinforcing elements tying the two slab sections together.

2. A composite building slab comprising a body of concrete divided into two sections along a median plane lying parallel with its major faces, the interior face of each of said sections having depressions which cooperate with the corresponding depressions in the other section to form interior openings in the composite slab, waterproofed fibrous material lining substantially the 55 entire inner face of each slab section, non-hardening waterproof plastic material interposed between the waterproofed fibrous material at all points where portions of the two slab sections come together, and reinforcing elements tying 60 the two slab sections together.

3. A composite building slab comprising a body of concrete divided into two sections along a median plane lying parallel with its major faces, the interior face of at least one of said sections 70 having depressions which form interior openings in the composite slab, sheet material lining substantially the entire face of each slab section, non-hardening waterproof plastic material interposed between the sheet material at all points 75

- where portions of the two slab sections come together, and reinforcing elements tying the two slab sections together.
4. A composite building slab comprising a body of concrete divided into two sections along a median plane lying parallel with its major faces, the interior face of at least one of said sections having depressions which form interior openings in the composite slab, waterproofed fibrous material lining substantially the entire inner face of each slab section, non-hardening waterproof plastic material interposed between the waterproofed fibrous material at all points where portions of the two slab sections come together, and reinforcing elements tying the two slab sections together.
5. A building slab comprising a body of concrete, a metallic reinforcing structure embedded in the concrete, and means for clamping the slab to a similar slab comprising at least one metal member rigidly secured to a part of the metallic reinforcing structure and means for clamping said metal member to the corresponding metal member of another slab whereby the clamping forces react against said metal member and the metallic reinforcing structure.
6. A building slab comprising a body of concrete having interior openings, a metallic reinforcing structure embedded in the concrete having transverse strut elements, at least one metal member rigidly secured to one of said transverse strut elements and projecting into one of said interior openings, one of the walls of the slab having a hand hole communicating with the same interior opening near said metal member, and means for clamping said metal member to a corresponding metal member in an adjoining slab.
7. A building slab comprising a body of concrete having interior openings, a metallic reinforcing structure embedded in the concrete, and means for clamping the slab to an adjoining one comprising instrumentalities entirely concealed within the slab and including at least one metal member rigidly secured to the metallic reinforcing structure and which projects into one of said interior openings, one of the walls of the slab having a hand hole communicating with the same interior opening to permit access to said metal member, and means for clamping said metal member to a corresponding metal member in an adjoining slab.
8. A building slab in accordance with claim 7 in which said metal member is provided with a bolt hole and in which a tube cast in the concrete extends from said bolt hole to the end of the slab to receive a bolt.
9. A building slab comprising a body of concrete, a metallic reinforcement embedded in the concrete all elements of which are rigidly secured together to form a unitary structure, and means for clamping the slab to a similar slab comprising at least one metal member rigidly secured to a part of the unitary reinforcing structure and a bolt for clamping said metal member to the corresponding metal member of another slab whereby the clamping forces react against said metal member and the metallic reinforcing structure and whereby the metal structure is substantially continuous throughout all the slabs that are bolted together.
10. A composite building slab comprising a body of concrete divided into two sections along a median plane lying parallel with its major faces, the interior face of each of said sections having depressions which cooperate with the corresponding depressions in the other slab section to form interior openings in the composite slab, hollow core members cast within and lining said interior openings in the slab, non-hardening waterproof plastic material interposed between those portions of the slab sections that come into closest proximity, and reinforcing elements tying the two slab sections together.
11. A cellular concrete member suitable for use in the erection of a prefabricated building, said member being slab-like in form so that a number of such members may be directly connected together at their edge portions to constitute the walls, partitions, floors and roof of the building, one of the walls of said member being provided with a bolt hole extending from the exterior of the member to one of the cells in the member, and one of the walls of the member having a hand hole in the vicinity of the bolt hole whereby two of the slab-like members may be bolted together through the bolt holes of the two members by the access afforded by the hand holes.
12. A cellular concrete member in accordance with claim 11 in which the bolt hole is formed by a tube cast in the concrete.
13. A cellular concrete member suitable for use in the erection of prefabricated buildings which is slab-like in form so that a number of such members may be connected together to form the walls, partitions, floors and roof of the building, said member having a metallic reinforcement embedded in the concrete and a unitary part of which lies within one of the cells of the member, one of the walls of said member having a bolt hole extending from the exterior of the member to said cell and to said part of the metallic reinforcement, said part of the reinforcement having a bolt hole in alignment with the first mentioned bolt hole, and one of the walls of said member having a hand hole in the vicinity of said bolt holes whereby two of said members may be bolted together through the bolt holes in the two members by reason of the access afforded by the hand holes and whereby the bolting means will react against the metallic reinforcements.
14. In a building, at least two concrete slabs adapted to be clamped together to form at least a portion of a wall, partition, floor or roof, each of said slabs having a metallic reinforcement embedded in the concrete all elements of which are rigidly secured together to form a unitary structure, and means for clamping the adjoining slabs together comprising metallic retracting means reacting against the metallic reinforcements of the two adjoining slabs in a direction such as to retract the metallic reinforcement of one slab toward the metallic reinforcement of the adjoining slab, whereby the clamping forces are received by the metallic reinforcements and whereby the metal structure is substantially continuous throughout all the slabs that are clamped together.
15. A composite building slab comprising a body of concrete divided into two sections along a median plane lying parallel with its major faces, the interior face of at least one of said sections having depressions which form interior openings in the composite slab, non-hardening waterproof plastic material interposed between those portions of the slab sections that come into closest proximity, and reinforcing elements tying the two slab sections together.
16. A cellular concrete member suitable for use in the erection of a prefabricated building, said

member being slab-like in form so that a number of such members may be directly connected together at their edge portions to constitute the walls, partitions, floors and roof of the building, 5 one of the walls of said member having a hand hole communicating with one of the cells in the member, and clamping means whereby two of the

slab-like members may be connected together at their meeting edge portions, said clamping means being concealed within the members when they are clamped together and being accessible through said hand hole.
